(57) **CLAIM**

The ornamental design for a tomato cage panel, as shown and described.

DESCRIPTION

FIG. 1 is a perspective view of a tomato cage panel in accordance with the present invention;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is a perspective view showing the invention in use with no claim made to the portions shown by dashed lines.
